UTENSIL HOLDER

Robert F. Gardner, Racine, Wis., assignor to
S. C. Johnson & Son, Inc., Racine, Wis.

Application September 12, 1949, Serial No. 4,959

Term of patent 14 years

(Cl. D44—29)

To all whom it may concern:

Be it known that I, Robert F. Gardner, a citizen of the United States, residing at Racine, in the county of Racine and State of Wisconsin, have invented a new, original, and ornamental Design for a Utensil Holder, of which the following is a specification, reference being had to the accompanying drawing, forming part thereof.

Fig. 1 is a front elevational view of a utensil holder showing my new design.

Fig. 2 is a plan view of the bottom end of the utensil holder.

Fig. 3 is a cross-sectional view taken on line 3—3 of Fig. 1.

Fig. 4 is a perspective view of Fig. 1.

I claim:

The ornamental design for a utensil holder, as shown.

ROBERT F. GARDNER.
